ICE CRUSHER

William C. Callinan, Winsted, and Alfred W. Wakeman,
Durham, Conn., assignors to Dynamics Corporation of
America, New York, N.Y., a corporation of New York

Filed Sept. 16, 1963, Ser. No. 76,612

Term of patent 14 years

(Cl. D89—1)

Fig. 1

Fig. 2

Fig. 3

FIG. 4

FIG. 5

FIG. 6

FIG. 1 is a front perspective view of an ice crusher showing our new design with the spout cover in closed position;

FIG. 2 is a side view of FIG. 1;

FIG. 3 is a top view of FIG. 1;

FIG. 4 is a view similar to FIG. 1 but showing the spout cover in open position;

FIG. 5 is a side view of FIG. 4; and

FIG. 6 is a top view of FIG. 4.

We claim:

The ornamental design for an ice crusher, as shown.
